Patented July 14, 1914.

UNITED STATES PATENT OFFICE.

JAMES H. PEARSON, OF BLOOMFIELD, INDIANA, ASSIGNOR OF ONE-HALF TO THOMAS A. HENDERSON, OF BLOOMFIELD, INDIANA.

FENCE-POST.

1,103,536.

Specification of Letters Patent. Patented July 14, 1914.

Application filed September 6, 1912. Serial No. 719,021.

To all whom it may concern:

Be it known that I, JAMES H. PEARSON, citizen of the United States, residing at Bloomfield, in the county of Greene and State of Indiana, have invented certain new and useful Improvements in Fence-Posts, of which the following is a specification.

This invention relates to improvements in posts, and has for one of its objects to simplify and improve the construction and increase the efficiency and utility of devices of this character, and produce a post which may be constructed of any suitable size and adapted to posts employed for various purposes.

Another object of the invention is to provide a simply constructed post formed of a co-acting frame and an angularly arranged brace connected to the frame where-by the frame is reinforced and supported and any tendency to warp, twist or deflect is obviated.

Another object of the invention is to provide a simply constructed post which may be combined with a concrete base to support it in position.

With these and other objects in view, the invention consists in certain novel features of construction as hereinafter shown and described and then specifically pointed out in the claims, and in the drawings illustrative of the preferred embodiment of the invention, Figure 1 is a perspective view of one of the improved posts. Fig. 2 is a side elevation with the concrete base block in section. Fig. 3 is an enlarged sectional detail on the line 3—3 of Fig. 2. Fig. 4 is a section on the line 4—4 of Fig. 3.

Corresponding and like parts are referred to in the following description and indicated in all the views of the drawings by the same reference characters.

The improved post may be constructed of any required size and employed for various purposes such as fence posts, gate posts, telegraph posts, trolley line posts, and the like, but for the purpose of illustration is shown applied to an ordinary fence post, but it will be understood that it is not designed to limit the invention to any specific form or size of post.

The improved post is preferably constructed of a body portion formed from a single strip of metal, preferably a channel bar, and bent intermediate its ends to form

spaced sides 10—11 with the channel side inwardly. At their terminals the sides 10—11 are bent outwardly at right angles to the longitudinal plane of the sides to form "feet" to assist in holding the post in the ground or in a concrete base, as hereafter explained. For an ordinary fence post a section of the channel bar is employed of about three fourths of an inch in width, but this dimension may be varied if required. The section of the channel bar to form the post is bent intermediate its ends into elongated U-shape and the terminals of the bar bent outwardly at right angles to form the "feet" 12—13 with the channels of the bar 70 presented inwardly.

Located between the sides 10—11 of the post is a brace member formed of a single bar 14 bent intermediate the ends into reversely angular portions with the brace at its bends engaging in the channels of the sides as shown. At its lower end the brace member is bent at right angles to the longitudinal plane of the post as shown at 15 and the terminal of the right angle portion 80 bent upwardly as shown at 16 against the inner face of one of the channel bars. At its upper end the brace 14 is slightly curved to conform substantially to the bend of the main post as shown at 17. To secure the 85 brace firmly to the sides 10—11 the material of the sides, or the flanges which form the channel, are compressed or bent inwardly over the brace at its bends as represented at 18, the material of the flanges being thus 90 stretched and tightly "crimped" against and over the outer edges of the brace material. This arrangement forms a very rigid and firm holding means between the brace and the side members of the post, and these 95 portions require no other fastening means. The flanges of the side members are likewise compressed in the same manner over the terminals 16—17 as shown. By this means it will be obvious that a very strong and 100 durable and compact post is produced in which the minimum of material is used with the maximum of strength and durability. The brace member 14 being arranged in oblique sections firmly braces the post and enables the post to firmly resist all tendency to twist or be deflected or the parts to be otherwise displaced.

In practice the lower portion of the post including the outer terminals 12—13 is em- 110

bedded in a mass of concrete represented conventionally at 19, and designed to be embedded in the ground where the post is erected. By this means the out-turned terminals 12—13 form anchors to firmly hold the post within its base.

Having thus described my invention, what I claim is:

1. A post comprising a body formed of channel bar bent to form spaced sides, each of said sides having inwardly directed flanges on its margin, and a brace comprising a flat bar bent into a plurality of reversely directed, angularly related portions bearing at the bends in the channels formed by the channels of the bar and having a width equal to the width between said flanges, the lateral flanges of the said sides at opposed portions being inwardly forced at a plurality of separated points to form lips engaging over the inner faces of the angular portions of the brace.

2. A post comprising a body including sides spaced apart, each of said sides being formed with inwardly directed lateral flanges, a brace disposed between said sides and comprising a bar having a width equal to the width between said flanges, the body of the bar being formed with a plurality of reversely directed, angularly related portions which bear at their bends in the channels formed by said inwardly turned flanges, the terminal ends of said brace being inserted between the flanges and being angularly bent,

and lips formed upon the sides by bending in opposite portions of the flanges at spaced points, said lips engaging over the inner faces of the angular portions of said brace.

3. A post including a body formed from a single length of channel bar bent to form spaced sides, each of said sides having inwardly directed flanges on its margin, the lower ends of the legs or sides being outwardly bent, and a brace comprising a flat bar bent into a plurality of reversely directed, angularly related portions bearing at the bends in the channels formed by the flanges of the bar and having a width equal to the width between said flanges, the lateral flanges of the said sides at opposite portions being inwardly forced at a plurality of separated points to form lips engaging over the inner faces of the angular portions of the members, the upper terminal end of said brace being inserted between the flanges of one side or leg and being angularly bent, the lower end of the brace being extended transversely from one leg or side to the opposed leg or side and being then angularly bent and engaged by inwardly bent portions of said flanges.

In testimony whereof I affix my signature in presence of two witnesses.

JAMES H. PEARSON. [L. S.]
